FIG. 3.

INVENTOR.

Charles W. Bryson.
BY

Bates & Macklin
ATTORNEY.

UNITED STATES PATENT OFFICE.

CHARLES W. BRYSON, OF CLEVELAND, OHIO, ASSIGNOR TO HOWARD L. WADSWORTH,
OF CLEVELAND, OHIO.

SAND-MIXING DEVICE.

Application filed May 17, 1919, Serial No. 297,887. Renewed December 23, 1920. Serial No. 432,890.

To all whom it may concern:

Be it known that I, CHARLES W. BRYSON, a citizen of the United States, residing at Cleveland, in the county of Cuyahoga and State of Ohio, have invented a certain new and useful Improvement in Sand-Mixing Devices, of which the following is a full, clear, and exact description, reference being had to the accompanying drawings.

10 This invention relates to sand mixing machines of a type adapted to be moved over the sand thrown in a pile or ridge on the floor and the general object of the invention is to provide a simple, efficient machine for 15 thoroughly manipulating, working and mixing of the sand, whereby it is lightened and its ingredients blended. A more specific object of the invention is to provide a machine, adapted to move over such a pile or ridge 20 by suitable propelling means, and having rotary mixing devices provided with blades adapted to engage the sand and mix or knead it and throw it rearwardly with relation to direction of travel of the machine. 25 In devices heretofore used it has been customary to provide kneading devices on a horizontal axis and in the use of which difficulties are encountered in attempting to treat the pile entirely to its base, particularly in 30 that the sand is unduly scattered.

This invention contemplates arranging kneading devices on a vertical axis and having the blades extended substantially upright and revolving about such axis as the 35 truck moves over the pile, whereby the entire pile may be treated without difficulty and the sand may be tossed to a certain extent through the air and at the same time leave it in a narrow ridge or pile substantially 40 as before the machine passed over it.

My invention contemplates the use of various adjustments in the machine, as for example, vertical adjusting of mixing devices so they may come nearer the bottom of the pile or be lifted somewhat above the same if desired. This present invention is more fully described in connection with the accompanying drawings and the essential characteristics are summarized in the 50 claims.

In the drawings Fig. 1 is a side elevation of my sand mixer; Fig. 2 is a plan of the same; Fig. 3 is the end elevation looking

forwardly from the rear end of the sand mixer. 55

Describing the sand mixer as shown by use of reference characters to designate its parts, 1 and 2 indicate respectively forward and rear upright members of a frame having longitudinal members 3 and 4 connecting the upright members, while transverse members 5 and 6 are connected with the upright and longitudinal members by any suitable means, as for example, gusset plates. The members 5 are preferably positioned forwardly from the lower ends of the uprights and brace members 7, shown as extending from the lower ends of the uprights to members 5 at such an angle that the lower portion of the frame forms, in effect, an arch to clear the pile of sand. 60 65

The frame just described may be of any suitable construction; it is preferably supported on four wheels, the forward wheels 8 being steering wheels, while wheels 9 are driving wheels. The wheels 8 are shown as carried on swiveled axle members 10, embracing vertical extensions 11 of the frame members 1, while forwardly extending arms 12 are pivotally connected by links 13 with a rock arm 15 at the lower end of the steering column 16, shown as carrying a suitable steering wheel 18. 70 75 80

The driving of the vehicle may be accomplished in any suitable manner, for example, I have shown an electric motor 20, having a sprocket 21, driving a sprocket chain 22, running over a sprocket wheel 24, rigid on the rear axle 25, which is in turn rigid with the wheels 9. The electric power for the motor 20 may be supplied either by the batteries carried by the frame or by a suitable flexible lead wire where the vehicle has a short region of travel, or by trolley if desired. 85 90 95

The sand mixers proper are shown as comprising drums 30 of any suitable construction adapted to rotate about a vertical axis and provided with radial plates 32. The blades of the opposing drums slightly overlap, as the drums rotate in opposing directions. It is desirable to have these drums vertically adjustable. Accordingly shafts 33 on which the drums are carried are mounted in bearings 34, carried by cross members 35 of a frame adjustably supported 100 105

2
by the main frame, the cross member 35 being intermediate of the ends of the frame and shown as connected with longitudinal channel members 36, which are braced near 5 their ends by transverse members 38. The members 36 rest against the inner sides of the uprights 1 and 2 and bolts 40, connecting these members extend through vertical slots 41, in the uprights to allow vertical 10 adjustment while allowing the frame carrying the mixers to be securely held in any desired position.

The raising and lowering of this frame may be accomplished by any suitable means, 15 as for example, vertical racks 45 rising from the members 38 and rigid therewith and which are engaged by pinions 46, on longitudinal shafts 48, intermediately connected by a sprocket chain 49 running over 20 sprockets 50 on the ends of shafts 48, whereby a suitable hand crank 52 may be used to rotate both shafts and raise the frame evenly. On the upper ends of the shafts 33 are bevel gears 60, driven by 25 pinions 62 on a shaft 64, having suitable bearings 65, carried on the frame member 36. The shaft 64 may be driven by a sprocket wheel 67 over which runs a chain shown at 68, in turn driven by a pinion 69 on the 30 armature shaft of motor 70.

It will be seen that the arrangement of the pinions 62 on the shaft 64 causes the drums 30 to rotate in opposite directions, preferably that shown by arrows in Fig. 2, 35 whereby the inner sides of the drums move rearwardly with the relation to the movement of the truck. If desired, however, the motor 70 may be reversible and the truck may be run in opposite directions, so that 40 direction of the drums may be such that the inner sides move rearwardly with the relation to the direction of movement of the truck, irrespective of whether the truck is moving forwardly or backwardly with 45 relation to its steering and driving wheels.

In the operation of my device a pile or ridge of sand is heaped on the floor or other suitable support. Assume for instance it is 50 —S—. The truck is moved over this ridge, longitudinally along the same, and the motor 70 is driven in such direction as to cause the drums to rotate in direction of the arrows in Fig. 2. Thus the ridge of sand is 55 passed through between the drums by means of blades 32 thereon and thrown rearwardly. By regulating the speed of these drums the sand may be thrown into a pile or ridge of substantially the same height and size as 60 before, whereby this process may be indefinitely repeated by running the truck forwardly and back over the same without manually handling the sand. In Figs. 1 and 3 the drums are shown as raised some- 65 what above the floor, as may be sometimes

desirable, but by adjustment of the frame carrying the drums they may be raised or lowered to work only the upper portion of the ridge or pile of sand, or to work the entire pile substantially to the floor. 70

Having thus described my invention, what I claim is:

1. In a sand mixing machine, the combination of a vehicle adapted to move over a pile of sand, intermeshing paddle wheels 75 carried by the vehicle, the blades of said paddle wheels having substantially flat impacting surfaces and means for rotating said paddle wheels as they are advanced through the sand, whereby the latter is 80 thoroughly kneaded and mixed and left in substantially the same character of pile as before the operation.

2. In a sand mixing apparatus, the combination of a vehicle adapted to move over 85 a pile of sand, cooperating rotary elements carried by the vehicle and having radial projecting blades thereon, in intermeshing engagement and having substantially flat impacting surfaces, and means for rotating 90 these elements on vertical axes, so that the blades move in the same direction at the inner side of each element, whereby the blades are thrust into the sand by movement 95 of the vehicle and the sand is pressed together with a kneading action as the blades approach and is further cut as the blades of one element pass those of the other elements, said rotary elements leaving the sand in substantially the same character of a pile as 100 before cutting.

3. In a sand mixing machine, the combination of a frame having supporting wheels, means for driving the wheels, a second frame extending transversely of said 105 first mentioned frame and adapted to be adjusted vertically, drums mounted on vertical axes intermediate the ends of the adjustable frame, having radially extending blades, said blades being substantially 110 rectangular and vertically mounted adapted to intermesh and means for rotating said drums in opposite directions.

4. In a sand mixing apparatus, the combination of a vehicle body, a rectangular 115 frame mounted therein, cooperating paddle wheels on vertical axes intermediate the ends of said frame, and interconnected geared shafting coaxing with vertical rack bars adjacent to the corners of the frame, whereby the height of the paddle wheels 120 may be varied.

5. In a sand mixing machine the combination of a vehicle body, a frame supported horizontally therein, sand mixing members comprising intermeshing vertical blades mounted intermediate the ends of said frame, and means for raising and lowering 125 said frame comprising shafts on said body parallel with the side members of said 130

frame, having gears in meshing engagement with rack bars on said frame.

6. In apparatus of the class described, the combination of a vehicle body, a frame mounted therein, vertically arranged paddle wheels mounted intermediate the ends of said frame and rotatable in opposite directions, means for adjusting the height of said frame, said means comprising rack

bars extending vertically upward from the corners of said frame, horizontal shafts mounted on opposite sides of said body having gears meshing with said rack bars, and means connecting said shafts whereby the frame may be raised or lowered evenly. 15

In testimony whereof, I hereunto affix my signature.

CHARLES W. BRYSON.
